UNITED STATES PATENT OFFICE.

WILLIAM H. HEYNE, JR., OF PASSAIC, NEW JERSEY.

TICKET-PRINTING MACHINE.

Application filed December 6, 1923. Serial No. 678,881.

To all whom it may concern:

Be it known that I, WILLIAM H. HEYNE, Jr., a citizen of the United States, residing at Passaic, in the county of Passaic and 5 State of New Jersey, have invented certain new and useful Improvements in Ticket-Printing Machines, of which the following is a specification, reference being had therein to the accompanying drawings, which 10 form a part thereof.

My invention relates to ticket printing machines, and more particularly to a machine adapted for use in printing tickets to be attached by clothing manufacturers to different garments or parts of garments in a suit of clothes.

In the manufacture of clothing, it is a common practice to lay a considerable number of strips of cloth upon a cutting table, 20 superimposed one upon the other in a number of layers, varying with different manufacturers. The pieces of cloth thus laid may all be of the same style, quality, and weight of goods, or the different layers may 25 vary in these respects. Even when the different layers of cloth are of the same color, weight and style, it is desirable to have the garments of each suit made from cloth from the same piece of goods, since there may be 30 slight variations in the finish or color of different pieces, which would be apparent if one garment or part of a garment be made from one, and another garment or part of a garment be made from another, piece of goods.

Owing to this condition, different garments or parts of garments as they are cut have affixed thereto, one of a sequence of similar tickets so that when these parts are 40 made into the garments by busklemen, it is possible, by means of such tickets, to readily identify the different garments entering into a suit, and permit the completed garment to be accurately collated and accounted for, even though tailoring of the garment be done at divergent points by entirely different busklemen.

The tickets used for this purpose are of small dimensions, and ordinarily have impressed thereon corresponding identifying numbers, letters or emblems for all the different garments of the suit, which identifying marking is associated with a shade or model number. Such tickets also have size 50 markings, and what is known as a "lot" number, which is a manufacturer's identi-

fication mark by which the number of suits produced from a given quantity of cloth may be checked.

A machine embodying my invention is so constructed that notwithstanding the necessary spacing of the various mechanisms for impressing these identifying marks upon the tickets, because of the size of these distinct mechanisms as compared with that of the tickets to be printed, it may be used to print these arbitrary identification markings upon succeeding tickets in close relation, with great rapidity and in the same spaced relation upon each ticket.

The printing mechanism of a machine embodying my invention embodies therein a platen or impression cylinder having associated therewith a rotatable member provided with a sequence of independent printing elements at spaced intervals about a common axis. One of these elements is adapted to impress upon the tickets, a model or style marking consisting of numbers, letters or emblems, or a combination of these, 55 in conjunction with what may be termed a suit number. Another of these elements is adapted to print digits, letters or emblems, or a combination of such, indicating the "lot," or a certain lot of work. The third 60 of said elements is adapted to impress numbers indicating the size of different garments entering into the suit. Each of these elements is in the nature of a numbering head, which has a plurality of independently rotatable wheels thereon normally held against movement, but capable of independent adjustment so that the various markings to be impressed upon different groups of 65 tickets may be quickly changed at will, 90 according to changing manufacturing conditions in a shop.

The printing element which is used for impressing the model or style marking and the garment numbers upon the tickets, includes therein a numbering head, one portion of which is capable of being progressively or intermittently actuated, and another portion of which, (that portion used for printing the model or style indicia) being manually operative only.

In conjunction with the printing couple, including the impression platen and the rotary member carrying the three elements above referred to, a machine embodying my invention is so constructed that the element for impressing the suit numbers upon the

5 tickets will be automatically actuated by means of a mechanism which is operative only upon the digit or other character wheels used for impressing the suit numbers. This mechanism while actuated with each rotation of the rotary member carrying the various printing elements, is of itself capable of being so set that the same number will be printed an indefinite number of times without change, or a definite number of times with a change after the completion of this number of impressions.

10 In a machine embodying my invention, I provide a strip feeding mechanism operative 15 in synchronism with the rotary movement of the platen cylinder, the movement of which cylinder, however, will be prevented at all times excepting when each printing element is in the printing relation to said 20 cylinder, during which time a spacing mechanism is operative upon the impression cylinder so as to impart timely actuation to the cylinder at different points during each rotation of the rotary member carrying the 25 printing elements to permit the making of the impression and secure the desired spacing between impressions.

30 The strip of previously printed tickets with blank spaces thereon is mounted in reel form with relation to the printing couple, a simple and convenient guiding mechanism being provided which will have the two fold effect of directing this strip between the elements of the printing couple and maintaining it in proper relation to the impression cylinder at all times while the strip is passing through the machine.

35 The impression cylinder is so constructed that the strip at all times during its movement is prevented from having any movement independently of said impression cylinder, thus permitting the intermittent actuation of this cylinder as each impression is being made to impart the desired positive movement to the strip to secure the desired spacing, it being understood that unequal spacing may be secured by imparting variable movement to said cylinder during such feeding intervals.

40 The inking mechanism employed is of a nature which will readily adapt it for use in and about a clothing shop, where labor skilled in the handling of ordinary printing presses and inking mechanisms therefor, is ordinarily not found.

45 The invention consists primarily in a ticket printing machine embodying therein a printing couple, one of the members of which is provided with a plurality of spaced printing elements, each of said elements including therein a sequence of independently adjustable character wheels, means whereby some of the character wheels upon one of said elements may be automatically and progressively actuated, and the other member

50 of which consists of a rotatable impression cylinder, means whereby said printing element carrying member may be rotated, and means for directing a strip into the printing relation between said members; and in such 70 other novel features of construction and combination of parts as are hereinafter set forth and described, and more particularly pointed out in the claims hereto appended.

55 Referring to the drawings,

Fig. 1 is a front view of a ticket printing machine embodying my invention, with portions thereof broken away;

Fig. 2 is a plan view of said machine;

Fig. 3 is a plan view with the printing 80 element carrying member removed from the machine and the back frame shown partly in section;

Fig. 4 is a back view of the machine adjacent the printing elements with the back 85 frame broken away; and

Fig. 5 is a perspective view of a portion 90 of the impression cylinder, and of the mechanism for imparting intermittent movement thereto.

Like numerals refer to like parts throughout the several views.

10 In the embodiment of my invention shown in the drawings, the base of the machine 10 is provided with extensions 11 having suitable feet 12 thereon. This base is provided with a back frame 13 having a laterally extending projection 14 supporting a spindle or arbor 15 for a roll of previously notched and weakened tickets in strip form. This 100 strip is indicated at 16. The end of the spindle is screw-threaded, and suitable side plates 17 are mounted upon said spindle and are secured in relation to the roll by means of a butterfly nut 18, or other securing 105 means.

110 The printing couple consists of a printing element carrying member 19 having a plurality of independent, spaced printing elements 20, 21 and 22 respectively, secured thereto at different points of the periphery of this member, and between the opposite side plates thereof; and a rotatable impression cylinder 23 mounted in the base 10 at a point where its surface is in a position to be engaged by the printing elements upon the member 19. The impression cylinder 23 may be made of any desired material, and I have found that no blanket or other makeready is required for this cylinder, highly satisfactory results being secured with the use of the metal cylinder having an integral impression surface.

115 The side plates of the member 19 are mounted to rotate idly upon a spindle 24 fixedly secured with relation to the back frame 13.

120 The member 19 and the printing elements carried thereby are adapted to be rotated in any desired manner as by means of the hand 125 130

- cran; 25, the impression cylinder 23 being positively rotated during each printing and spacing interval but held against movement between impressions by co-operating members carried respectively by the member 19 and the cylinder 23, and intermediate connecting means, which limit the feeding movement of the strips to a distance required to secure the desired impressions and spacing
- 10 between the impressions upon each ticket and upon succeeding tickets entirely independently of the peripheral traverse of the printing elements during each cycle of operations of the machine.
- 15 Ink is applied to the various printing elements by means of an inking roller 26 consisting of felt, or some other absorbent material which may be saturated with the ink. This roller is removably mounted in a frame
- 20 27 pivoted at 28 to the extension 14, a set screw 29 being provided by means of which the frame 27 may be locked in any adjusted position to secure the desired pressure relation between the roller 26 and said printing
- 25 elements.

Adjacent the impression cylinder 23 is an oscillatory hollow guide member 30 through which the strip 16 is adapted to pass, said member having a curved end 31 extending close to the printing position so as to force and hold the strip 16 firmly against the impression cylinder at this point. The guide 30 is acted upon by a spring 32 normally forcing the end 31 against the impression 35 roller or cylinder. The end 31 is bevelled off as shown to afford the proper clearance for the printing elements as they approach the impression cylinder.

Beyond the printing point is a stripper 32 bearing upon the cylinder 23 and adapted to direct the strip 16 below a guide roller 33 having enlarged shoulders 34 and 35 adapted to engage the opposite ends of the strip 16 while leaving a reduced portion intermediate these shoulders which will ensure the narrowed edge of the strip when starting a run, passing below this roller. The narrowed end of the strip is caused by triangularly notched portions at opposite edges thereof connected by weakened lines, as shown more particularly in Figs. 1 to 3 of the drawings.

To ensure the proper engaging relation between the impression cylinder and the printing elements, I mount the cylinder 23 upon an eccentric bushing 36 upon the shaft 37, so that said cylinder may be adjusted toward and from the shaft 24.

Each of the printing elements 20, 21 and 22 is composed of a sequence of independently rotatable character wheels such as are ordinarily found in numbering heads. The elements 21 and 22 are so constructed that the various character wheels may be independently adjusted or set, this adjustment

however, being manual. This general construction is common in what is known as "daters", wherein it is desired to change the position of these wheels only at fixed intervals. There are no automatic features in these printing elements 21 and 22, although if desired a drop cipher construction may be used, this construction also being old in numbering and dater heads.

The element 20, however, is provided with a sequence of such digit wheels, two of which, those shown to the right of Fig. 2, being adapted to be automatically actuated by means of a swing frame 38 commonly used in automatic numbering heads for progressively actuating the digit wheels of such heads. The remaining wheels of the element 20 are adjustable only manually. This construction is employed because of the fact that the garment numbers change, without change in the shade or model numbers, and it is desirable to provide for the automatic variation of the garment numbers. In fact the construction as to the automatically actuated character wheels is the same as in ordinary numbering heads, my invention relating not to the detailed construction of this printing element, but to the manner of actuating the same in synchronism with the functioning of the printing element carrying member. In fact, if desired this element 20 may have incorporated therein those mechanisms by which the same number may be repeatedly printed for an indefinite length of time, or may be printed only once or a greater number of times before the automatic actuation of the wheels carrying the numbers or characters indicating the garments. The mechanism for securing this repeat or intermittent action is also old and well known in the numbering head art.

The swing frame 38 is provided with a pivot 39 projecting through a segmental slot 40 in the side plate of the member 19 adjacent the back frame 13 and entering a socket 41 in a link 42 carried by an eccentric strap 43 encircling an eccentric 44 fixed in relation to the back frame 13. By this construction the swing frame 38 receives one complete oscillation, direct and return, with each rotation of the member 19 so as to cause this swing frame to actuate the automatically actuated digit wheels upon the element 20 once with each rotation of the printing element carrying member unless the operative connection between this swing frame and the said digit wheels is so set as to vary the operative effect of the swing frame in the respects above referred to. The eccentric 44 is so set as to complete the oscillatory movement of the swing frame during the interval between succeeding impressions by the printing element 20. This mechanism for actuating the automatically operated wheels of the printing element 20

is entirely concealed by the printing element carrying member 19, and the construction and arrangement is such that under no circumstances can this mechanism get out of order while the machine is in operation, nor can its operative effect be modified in any way through a loss of adjustment in parts.

In a machine of the character to which my invention relates, in which the various identifying numbers and characters must be printed in closely spaced relation upon a strip having notches along the edge in the manner described, it is apparent that this strip must be fed with great accuracy in order to prevent the accumulation of error in the printing of a large number of tickets upon the strip, and that where the space between the impressions from a plurality of printing elements is very much less than the distance between the elements themselves, it is apparent that the means for feeding the strip must be so constructed that there can be only an intermittent movement of the strip, timed with relation to the printing interval and limited to a quantity of feeding movement required by the making of an impression and the spacing between succeeding impressions upon each ticket and the distance required to similarly place corresponding indicia upon succeeding tickets.

In the accompanying drawings, I have illustrated a mechanism which I have found highly satisfactory in permitting operation of the machine at fairly high speeds, and with a degree of accuracy which will prevent the development and accumulation of any such error as would cause irregularity in the positioning of impressions made upon each ticket, or upon succeeding tickets. This mechanism comprises a continuous gear wheel 45 carried by the impression cylinder 23 which is in constant mesh with an idler pinion 46. Meshing with the pinion 46 is an idler pinion 47, which pinion is adapted to be engaged by segmental rack sections 48, 49 and 50 carried by and rotatable with the side plate of the member 19 adjacent the back frame 13 of the machine. These segmental racks 48, 49 and 50 are fixed in their relation to the printing elements 20, 21 and 22 and so positioned that they will enmesh the pinion 46 substantially simultaneously with the initial engagement of the printing surfaces of the respective elements with the strip, thus causing the rotation of the impression cylinder 23 at the same peripheral speed as that of the printing element during the impression interval and following this interval to an extent to properly position the strip preparatory to the making of an impression by the succeeding printing element.

It will be noted that after the making of impressions upon one ticket by all of the

printing elements, the quality of feed of the strip, in the form of the invention shown, will be greater than is required between succeeding impressions upon the same ticket. The feeding mechanism described permits variation in the length of feed after the making of each impression by the use of segmental rack sections 48, 49 and 50 of different degrees in length. While, as shown in the drawings, this variance in feeding movement is confined to the movement of the strip between the impressions made by the elements 22 and 20, as by making the rack 50 longer than the racks 48 and 49, it is apparent that if required the construction may be extended to the spacing between the other printing elements.

To ensure the enmeshment of each of the segmental rack sections 48, 49 and 50 with the teeth of the pinion 47, and incidentally avoid any possible overrunning of the impression cylinder and a resultant excess feed of the strip, I so construct the pinion 47 and the member upon which the racks 48, 49 and 50 are formed, that all movement of the pinion 47 is prevented except during that interval when said racks are in engaging relation with said pinion. This construction is in the nature of a Geneva stop, and has the same operative effect, although I secure this result by a particular construction of the pinion 47. This pinion has a sequence of spaced long teeth 51 and interposed short teeth 52, and the teeth of the pinion 46 are wide enough to mesh with both the long and short teeth of the pinion 47. Both sets of teeth 51 and 52 are adapted to mesh with each of the racks 48, 49 and 50. The number of long teeth 51, however, will be greater as compared with the number of short teeth, in the portion of the pinion which engages the rack 50 to assure the proper spacing of the remaining long teeth. The short teeth 52 afford clearance at one side of these teeth for arcuate members 53, 54 and 55 of substantially the same radius as the racks 48, 49 and 50, said arcuate members being of a width to escape the teeth 52 and the ends of succeeding members being spaced apart a distance substantially equaling the length of the racks 48, 49 and 50 respectively. The long teeth upon the pinion 47 are adapted to engage said members 53, 54 and 55 respectively so that the movement of any rack 48, 49 or 50 out of mesh with the pinion 47, two long teeth 51 of the pinion 47 will, by engagement with said members immediately arrest all movement of the impression cylinder 23.

While the teeth of the respective racks 48, 49 and 50 project into the gap between succeeding arcuate members 53, 54 and 55, they are formed upon a plate 56 positioned rearwardly of said members as shown more particularly in Fig. 4, and project ra-

dially from the periphery of this plate so that as each rack passes out of mesh with the teeth 51 and 52 of the pinion 47, clearance is afforded to permit continued rotary 5 movement of the member 19.

Since the feeding movement of the strip 16 will thus result from the movement of the impression cylinder 23, and since this movement must continue after the making 10 of each impression to secure the proper spacing of the characters of the pinion, I provide said cylinder, adjacent the opposite edges thereof, with a sequence of rectilinearly opposite inwardly presented teeth 15 57 adapted to enter the triangular notches in the opposite edges of the strip 16, the opposite teeth of each sequence being spaced about the perimeter of said cylinder a distance equalling the distance between the 20 notches in the said strip. In this manner a positive uniform feed of the strip is secured and all likelihood of the development or accumulation of error is prevented.

If desired, the feet 12 may be secured to 25 the lugs 11 by means of screws as 58, which screws may also be utilized to secure the machine as a whole upon a suitable base board or table.

The operation of the herein described machine is substantially as follows:—

The end of the strip 16 is drawn from the roll and inserted through the channel in the guide 30 and below the projecting end 31 thereof, the guide being oscillated against 35 the tension of the spring 32 so as to permit the end of the strip to pass freely between said end 31 and the surface of the impression cylinder 23.

Before threading the strip in the manner described, it is essential to determine that the position of the printing element for impressing the upper line of characters upon the ticket, is in such relation to the impression cylinder as to make the impression upon the 45 desired part of each ticket.

It is apparent that as the strip is threaded in the machine, the forward notched end thereof will engage opposite teeth 57 and thus ensure accuracy in the positioning of 50 the foremost edge of the first ticket with relation to the printing couple.

Each of the printing elements 20, 21 and 22 upon the rotary member 19 should have the various printing wheels thereon set so 55 as to secure the desired impression, prior to the threading of the strip through the guide 30. This setting of the printing wheels is done by hand. When setting the element 20, the mechanism for controlling the operative 60 effect of the swing arm 38 is also set according to whether it is desired to have the printing wheels 39 actuated to change the characters with each rotation of the member 19, or after a given number of rotations, or to 65 have the characters on said wheels repeated

indefinitely. This capability of adjustment permits the adaptation of the machine to different shop systems.

When all the printing elements have been properly set, the member 19 is turned by 70 means of the hand crank 25. With the initial rotary movement of the member 19, the engagement of the arcuate member 55 with two of the long teeth 51, will prevent any movement of the impression cylinder 75 23. As the printing surface of the element 20, however, comes into engaging relation with the ticket, the teeth of the segmental rack 48 will mesh with the teeth 51 and 52 of the pinion 47, and thus through the pinions 47—46 and gear 45 impart positive rotary movement to the platen at the same peripheral speed as that of the printing element 20. The employment of two idler pinions 46 and 47 will ensure the proper direction of rotation of the impression cylinder. While the rack 48 is in mesh with the teeth of the pinion 47, the said pinion 47 will be in the gap between the arcuate members 53 and 55 so as to permit the free rotation of 80 said pinion and the mechanism actuated thereby. Immediately that the rack 48, however, passes out of mesh with the pinion 47, the long teeth 51 of said pinion will engage the arcuate stop member 53 and thus 85 arrest further movement of the impression cylinder 23 and hold this cylinder stationary until the rack 49 meshes with the pinion 47 in the same manner as that above described.

The small diameter of the ring 56 affords 90 the proper clearance between succeeding segmental racks upon said ring for the short teeth 52 on the pinion 47. This mode of operation permits any desired spacing of the characters upon each ticket as determined 95 by the length of the respective racks 48, 49 and 50.

In the form of the invention shown, the rack 50 is twice the length of the racks 48 and 49, since this rack is relied upon for 100 spacing the strip between the last number impressed upon one ticket and the first number impressed upon the following ticket, irrespective of the diameter of the rotary member 19 or of the distance between the 105 printing elements upon this member. Since the length of the racks 48, 49 and 50 is determined by, and coincident with, the length of the tickets, it is apparent that so far as 110 the printing operation is concerned, each ticket is printed under exactly the same conditions and there can be no accumulated error. The teeth 57 will prevent any shifting of the strip with relation to the impression cylinder, so as to destroy this condition 115 of absolute accuracy. The arcuate members 53, 54 and 55 prevent any overrunning of the impression cylinder, since these members, with the long teeth 51 of the pinion 47, 120 act as a Geneva stop for causing the inter- 125

mittent operation of the impression cylinder 23.

With each rotation of the member 19, the eccentric 44 will impart one direct and return reciprocation through the strap 43 to the link 42. This link, through the socket 41, will impart a direct and return reciprocatory movement to the swing frame 38 so as to secure the desired operative effect with relation to the digit wheels 39 upon the printing element 20. This effect may either be the progressive actuation of these wheels with each actuation of the swing frame 38, or intermittent actuation of said wheels by said swing frame, or if desired the swing frame may be made totally inoperative with relation to said digit wheels. This result is secured by the repeat mechanism found in ordinary numbering heads, and it is therefore not fully shown nor described in the present application.

The hand operation of the member 19 permits the rapid printing of these tickets in a quantity as desired. If in a certain lot of merchandise one hundred suits are to be made and seven tickets are to be applied to the cloth for each suit, the machine may be so set as to indicate the entire lot, the tickets being printed in groups of seven before any change of the wheels 39 is made by the swing frame 38. After the seventh full cycle of operations, however, there will be a change in said digit wheels, and a further group of seven similar tickets will be printed. If it is desired to run only two or three tickets in a group, the printing element 20 may be set so that the tickets will be printed in groups of two or three.

If the pile of cloth has thirty layers, the different layers being of goods of different styles, the machine is stopped after the desired number of tickets for one style have been printed, and the manually operative wheels upon the printing element 20 are set to change the indicated shade or model number. Since all of the garments which are made from a single pile of cloth will ordinarily be of the same size, no resetting of the wheels of the element 21 or of the element 22 will be required, since the goods of one pile will ordinarily be in the same lot. If different sizes of garments, however, be cut from one pile, it will be necessary for the user of the machine to change the size number to conform to the size of the different garments.

The printed tickets are delivered at the cutting table, and after the garments are cut, they are distributed with relation to the proper garments, and attached to some part of the cloth forming each garment, where they remain during all of the time when tailoring work is being done upon the garment and until they are delivered to the stock room in completed form. With the

tickets attached, it is immaterial where tailoring is done upon the garments, since when they are returned to the stock room, the tickets will indicate the garments entering into each suit, so that these garments may be quickly collated.

It is apparent that with the arrangement and construction of printing elements herein shown and described, the machine may be used to print tickets to conform to any manufacturing system which may be adopted, and that tickets may be printed only as required, thus permitting the use of blank strips in making all tickets and avoiding those complications which frequently arise when previously printed tickets are used.

It is not my intention to limit the invention to the precise details of construction shown in the drawings, it being apparent that such may be varied without departing from the spirit and scope of the invention.

The co-operating mechanisms carried by the member 19 and the impression cylinder 23, to wit: the segmental racks 48, 49 and 50 and arcuate members 53, 54 and 55 and the rack 45 and the intermediate mechanism consisting of the pinions 46 and 47, are essential to the invention either in the form shown or in an equivalent form, since this mechanism is relied upon to secure the desired close spacing of the reproduced characters upon the ticket in the desired close juxtaposition. Without such a mechanism it would be impossible to utilize printing elements of the character of those herein described, since impressions less than one and one-half inches apart cannot be made with such printing units.

Having described the invention, what I claim as new and desire to have protected by Letters Patent, is:—

1. A ticket printing machine embodying therein a printing couple, one of the members of which is provided with a plurality of spaced printing elements, each of said elements including therein a sequence of independently adjustable character wheels, means whereby some of the character wheels upon one of said elements may be automatically and progressively actuated, and the other member of which consists of a rotatable impression cylinder, means whereby said printing element carrying member may be continuously rotated, intermittently operative gearing between said last named member and the other member of the printing couple, whereby the impressions by the elements upon said other member may be brought closely together, and means for directing a strip into the printing relation between said members.

2. A ticket printing machine embodying therein a printing couple, one of the members of which is provided with a plurality of spaced printing elements, each of said ele-

- ments including therein a sequence of independently adjustable character wheels, means whereby some of the character wheels upon one of said elements may be automatically 5 and progressively actuated, and the other member of which consists of a rotatable impression cylinder, means whereby said printing element carrying member may be rotated, means for directing a strip into the printing relation between said members, and cooperating mechanisms carried by the members of said printing couple respectively and intermediate said members, whereby said impression cylinder will be positively rotated 10 as each printing element comes into the printing relation thereto and is held against rotation after said element has left the printing position and the strip has been fed to secure the proper spacing for the succeeding 15 impression.
3. A ticket printing machine embodying therein a printing couple, one of the members of which is provided with a plurality of spaced printing elements, each of said elements including therein a sequence of independently adjustable character wheels, means whereby some of the character wheels upon one of said elements may be automatically 20 and progressively actuated, and the other member of which consists of a rotatable impression cylinder, means whereby said printing element carrying member may be continuously rotated, intermittently operative 25 gearing between said last named member and the other member of the printing couple, whereby the impressions by the elements upon said other member may be brought closely together, an inking roller consisting of absorbent material adapted to be saturated 30 with ink, positioned in the path of movement of said printing elements, and means for directing a strip into the printing relation between said members.
4. A ticket printing machine embodying 35 therein a printing couple, one of the members of which is provided with a plurality of spaced printing elements, each of said elements including therein a sequence of independently adjustable character wheels, means whereby some of the character wheels upon one of said elements may be automatically 40 and progressively actuated, and the other member of which consists of a rotatable impression cylinder, means whereby said printing element carrying member may be rotated, means for directing a strip into the printing relation between said members, and means carried by said impression cylinder whereby movement of the strip with 45 relation to said cylinder is prevented.
5. A ticket printing machine embodying 50 therein a printing couple, one of the members of which is provided with a plurality of spaced printing elements, each of said elements including therein a sequence of independently adjustable character wheels, means whereby some of the character wheels upon one of said elements may be automatically 55 and progressively actuated, and the other member of which consists of a rotatable impression cylinder, means whereby said printing element carrying member may be rotated, a pivotally mounted frame having bearings whereby an inking roller may be removably mounted therein, the pivotal support for said frame extending parallel 60 with the axis of the member carrying the printing elements, means whereby said frame may be set in any adjusted position, an inking roller consisting of absorbent material adapted to be saturated with ink, 65 mounted in said bearings and positioned in the path of movement of the printing elements, and means for directing a strip into the printing relation between said members.
6. A ticket printing machine embodying 70 therein a printing couple, one of the members of which is provided with a plurality of spaced printing elements, each of said elements including therein a sequence of independently adjustable character wheels, means whereby some of the character wheels upon one of said elements may be automatically 75 and progressively actuated and including therein an actuating mechanism consisting of an eccentric fixed in relation to the axis of the member carrying the printing elements, a strap encircling said eccentric, a link connected with said strap, and a swing frame carried by the printing element, and the other member of which consists of a rotatable impression cylinder, 80 means whereby said printing element carrying member may be rotated, an inking roller arranged in the path of movement of said printing elements, and means for directing a strip into the printing relation between 85 said members.
7. A ticket printing machine embodying 90 therein a printing couple, one of the members of which is provided with a plurality of spaced printing elements, each of said elements including therein a sequence of independently adjustable character wheels, means whereby some of the character wheels upon one of said elements may be automatically 95 and progressively actuated, and the other member of which consists of a rotatable impression cylinder, means whereby said printing element carrying member may be rotated, means for directing a strip into the printing relation between said members, 100 and means carried by said impression cylinder whereby movement of the strip with relation to said cylinder is prevented.
8. A ticket printing machine embodying 105 therein a printing couple, one of the members of which is provided with a plurality of spaced printing elements, each of said elements including therein a sequence of independently adjustable character wheels, means whereby some of the character wheels upon one of said elements may be automatically 110 and progressively actuated, and the other member of which consists of a rotatable impression cylinder, means whereby said printing element carrying member may be rotated, means for directing a strip into the printing relation between said members, and a sequence of rectilinearly opposite inwardly presented teeth adjacent the opposite edges of said impression cylinder adapted to engage notches in the edge of the strip and prevent movement of the strip relative 115 to said cylinder.

8. A ticket printing machine embodying 65
therein a printing couple, one of the mem-
bers of which is provided with a plurality
of spaced printing elements, each of said ele-
ments including therein a sequence of inde-
pendently adjustable character wheels,
means whereby some of the character wheels
upon one of said elements may be auto-
matically and progressively actuated, and
the other member of which consists of a ro-
tatable impression cylinder, means whereby
said printing element carrying member may
be rotated, an oscillatory guide member ad-
jacent said impression cylinder and having
a forwardly projecting end adapted to en-
gage said cylinder, whereby a strip is direct-
ed into the printing relation between said
members, and a spring acting upon said
guide to normally force its projecting end
20 toward said impression cylinder. 80

9. A ticket printing machine embodying
therein a printing couple, one of the mem-
bers of which is provided with a plurality
of spaced printing elements, each of said
elements including therein a sequence of inde-
pendently adjustable character wheels,
means whereby some of the character wheels
upon one of said elements may be auto-
matically and progressively actuated, and the
other member of which consists of a rotatable
impression cylinder, means whereby said
printing element carrying member may
be rotated, an oscillatory guide member ad-
jacent said impression cylinder and having
a forwardly projecting end adapted to en-
gage said cylinder, whereby a strip is direct-
ed into the printing relation between said
members, and a spring acting upon said
guide to normally force its projecting end
25 toward said impression cylinder, a stripper
upon the side of said impression cylinder
opposite said guide, and a guide roller above
said stripper. 90

10. A ticket printing machine embodying
therein a printing couple, one of the mem-
bers of which is provided with a plurality
of spaced printing elements, each of said
elements including therein a sequence of inde-
pendently adjustable character wheels,
means whereby some of the character wheels
upon one of said elements may be auto-
matically and progressively actuated, and the
other member of which consists of a rotatable
impression cylinder, means whereby said
printing element carrying member may
be rotated, means for directing a strip into
the printing relation between said members,
a gear carried by said impression cylinder,
segmental racks adjacent said printing ele-
ments respectively carried by and rotatable
with the member carrying said elements, two
enmeshed intermediate pinions, one of which
is adapted to be intermittently engaged by
said racks, and the other of which is en-
meshed with the gear upon said impression
cylinder, whereby said impression cylinder
will be rotated when each of said elements
is in printing relation thereto, means where-
by rotation of said impression cylinder is
prevented except when said racks are
engaged with said pinions, and means carried
by said impression cylinder whereby move-
ment of the strip in relation thereto is pre-
vented. 100

11. A ticket printing machine embodying
therein a printing couple, one of the mem-
bers of which is provided with a plurality
of spaced printing elements, each of said ele-
ments including therein a sequence of inde-
pendently adjustable character wheels,
means whereby some of the character wheels
upon one of said elements may be auto-
matically and progressively actuated, and the
other member of which consists of a rotatable
impression cylinder, means whereby said
printing element carrying member may be
rotated, means for directing a strip into
the printing relation between said members,
a gear carried by said impression cylinder,
segmental racks adjacent said printing ele-
ments respectively carried by and rotatable
with the member carrying said elements, two
enmeshed intermediate pinions, one of which
is adapted to be intermittently engaged by
said racks, and the other of which is en-
meshed with the gear upon said impression
cylinder, whereby said impression cylinder
will be rotated when each of said elements
is in printing relation thereto, and means where-
by rotation of said impression cylinder is
prevented except when said racks are
engaged with said pinions. 110

12. A ticket printing machine embodying
therein a printing couple, one of the mem-
bers of which is provided with a plurality
of spaced printing elements, each of said
elements including therein a sequence of inde-
pendently adjustable character wheels,
means whereby some of the character wheels
upon one of said elements may be auto-
matically and progressively actuated, and the
other member of which consists of a rotatable
impression cylinder, means whereby said
printing element carrying member may
be rotated, means for directing a strip into
the printing relation between said members,
a gear carried by said impression cylinder,
segmental racks adjacent said printing ele-
ments respectively carried by and rotatable
with the member carrying said elements, two
enmeshed intermediate pinions, one of which
is adapted to be intermittently engaged by
said racks, and the other of which is en-
meshed with the gear upon said impression
cylinder, whereby said impression cylinder
will be rotated when each of said elements
is in printing relation thereto, means where-
by rotation of said impression cylinder is
prevented except when said racks are
engaged with said pinions, and means carried
by said impression cylinder whereby move-
ment of the strip in relation thereto is pre-
vented. 120

13. A ticket printing machine embodying
125

- therein a printing couple, one of the members of which is provided with a plurality of spaced printing elements, each of said elements including therein a sequence of independently adjustable character wheels, means whereby some of the character wheels upon one of said elements may be automatically and progressively actuated, and the other member of which consists of a rotatable impression cylinder, means whereby said printing element carrying member may be rotated, means for directing a strip into the printing relation between said members, a gear carried by said impression cylinder, a pinion enmeshed with said gear, a second pinion enmeshed with said last named pinion and having some short and some long teeth, segmental racks adjacent said printing elements respectively carried by and rotatable with the member carrying said elements and so positioned as to mesh with both the long and the short teeth upon said last named pinion, whereby said impression cylinder will receive intermittent feeding movement as each of said printing elements comes into the printing relation thereto, and segmental arcuate members intermediate said racks respectively so positioned as to engage the long teeth of said pinion only, whereby rotation of said impression cylinder is prevented except when said racks are engaged with said pinion. 65
15. A ticket printing machine embodying therein a frame having an extension, a spindle carried by said extension and adapted to receive a strip of blank tickets, a printing couple mounted in said frame, one of the members of which is provided with a plurality of spaced printing elements, each of said elements including therein a sequence of independently adjustable character wheels, means whereby some of the character wheels upon one of said elements may be automatically and progressively actuated, and including therein an actuating mechanism consisting of an eccentric fixed with relation to the axis of the member carrying the printing elements, a strap encircling said eccentric, a link connected with said strap, and a swing frame carried by said printing element, and the other member of which consists of a rotatable impression cylinder, a pivotally mounted frame having bearings whereby an inking roller may be removably mounted therein, the pivotal support for said frame extending parallel with the axis of the member carrying the printing elements, means whereby said frame may be set in any adjusted position, an inking roller consisting of absorbent material adapted to be saturated with ink, mounted in said bearings and positioned in the path of movement of the printing elements, an oscillatory guide member adjacent said impression cylinder and having a forwardly projecting end adapted to engage said cylinder whereby a strip is directed into the printing relation between said members, a spring acting upon said guide to normally force its projecting end toward said impression cylinder, a stripper upon the side of said impression cylinder opposite said guide, a guide roller above said stripper, a sequence of rectilinearly opposite inwardly presented teeth adjacent the opposite edges of said impression cylinder adapted to engage notches in the edges of the strip and prevent movement of the strip relative to said cylinder, a gear carried by said impression cylinder, a pinion enmeshed with said gear, a second pinion enmeshed with said last named pinion and having a plurality of groups composed of some short and some long teeth, the number of long teeth in some of these groups being greater than in the others, segmental racks adjacent said printing elements respectively carried by and rotatable with the member carrying said elements and so positioned as to mesh with both the long and the short teeth of the groups upon said last named pinion, some of said racks having a greater number of teeth than the others, whereby said impression cylinder will receive intermittent feeding movement as each of said printing elements comes into the printing relation thereto, and segmental 70

some of said racks having a greater number of teeth than the others, whereby said impression cylinder will receive intermittent feeding movement as each of said printing elements comes into the printing relation thereto, and segmental arcuate members intermediate said racks respectively so posi-

tioned as to engage the long teeth of said pinion only, whereby rotation of said impression cylinder is prevented except when 10 said racks are engaged with said pinion.

In witness whereof I have hereunto affixed my signature, this 26th day of October, 1923.

WILLIAM H. HEYNE, JR.
